WRINGER MOP

Filed July 29, 1929

Harry Hertzberg Inventor

By his Attorney

Martin Joachimson

UNITED STATES PATENT OFFICE

HARRY HERTZBERG, OF BROOKLYN, NEW YORK

WRINGER MOP

Application filed July 29, 1929. Serial No. 381,949.

This invention relates to wet mops, and more particularly to mop heads which are intended to be mounted upon handles and which may be wrung by stretching the mop strands along the handle and twisting them around the same.

It is the object of the present invention to provide a mop head of this type which is of extremely simple construction, which can easily be released from the handle and which is attached to the lower end of the handle by resilient and yielding attaching means.

With these objects in view the invention consists in certain novel features of construction, combination of elements and arrangements of parts which will be fully described in these specifications and finally be pointed out in the appended claims.

The invention is shown in the accompanying drawings which form a material part of these specifications and in which:

Fig. 1 is an elevation of my wringer mop in stretched condition. A part of the mop strands is cut away to show the inner parts.

Fig. 2 is an elevation of the mop of Fig. 1 when the same is twisted for wringing.

Fig. 3 is an elevation of the mop of Figs. 1 and 2 when the same is in position for mopping.

Fig. 4 is a detail elevation of sleeve 12 parts of which are cut away to show the fastening of the mop strands thereto.

Fig. 5 is a detail showing the fastening of the mop strands at the lower end of the handle. The resilient connector 30 and tie wires are shown in section, and a part of the mop strands is removed to show the interior.

Referring to the drawings my wringer mop consists of a standard round mop handle 11 which is provided with a threaded portion 11^a of smaller diameter at its lower extremity. The threaded portion 11^a of the handle is enclosed within a helical coil-spring 30 of wire, wound to have the same pitch as the threads on 11^a and with a more closely wound portion of smaller diameter extending beyond the bottom 11^b of the mop handle. In this manner the turn 30^b of the coil provides a shoulder within the coil, forming a stop

for the mop handle, so that the upper part of the spring acts like a screw-socket with closed bottom, for the mop stick. On the outside of the coil turn 30^b, being of larger diameter than 30^b forms also a shoulder on 55 the outer face of the coil.

The mop material consists preferably of rope-like strands which are folded upon themselves at their middle parts for forming loops. These loops are tied by tie wires 13^a and 13^b to a preferably wooden sleeve mounted to slide on the mop handle 11. Sleeve 12 is provided with two encircling grooves of saw-tooth shape providing two transverse shoulders 12^a and 12^b into which the mop strands 20 are pressed by the tie wires 13^a and 13^b. It will be seen from Fig. 4 that only one layer of mop material is passing through the grooves for 13^a and 13^b and that the outer layer of mop cords covers the tie wires. By this manner of fastening a very close contact of cords and sleeve and an extremely strong joint, which resists the pulling and twisting better than other methods of fastening, is provided.

The ends of the mop strands are tied together by a tie wire ring 14^b below the end of the coil spring at 30^c and fastened to the coil at the shoulder 30^a by a tie wire 14^a which presses the cords into the space between turns 30^a and 30^b and thereby produces a very tight connection at that point. If tie wire ring 14^a is somewhat loose, the lower part of the coil can be screwed into the hollow part of the ball-shaped mop cords until the bottom-turn 30^c presses the cords against the upper face of ring 14^b, stretching the ball longitudinally into oval shape until the shoulder at 30^a prevents further movement, 90 then wire 14^a is closely tied by twisting the ends about each other. The part of the coil from 30^a downward provides a resilient center for ball 20^a which is a very desirable feature as the side of the ball and not only the 95 front edge of the mop stick can be pressed against the looped cords of Fig. 3 and against the floor surface while scrubbing.

It is obvious that the above described mop can be wrung by turning the sleeve 12 on 100

handle 11 and thereby twisting the mop cords 20 around the latter.

The very few and simple parts which enter in the construction of this mop permit its manufacture and sale at an extremely low price and in addition provide an implement which embodies valuable novel features.

Obviously the invention is susceptible of modification and arrangement of parts, and the right is herein reserved to make such changes as fall within the scope of the appended claims without departing from the spirit of the invention.

Having thus described my invention what I claim is:

15 1. A wringer mop comprising in combination a mop handle, a thread on one end of said handle, a helical coil of wire adapted to engage the threads on said handle, said coil extending beyond the end of said handle, a sleeve rotatably and slidably mounted on said handle and mop material having one end attached to said sleeve the other end covering said wire coil beyond the end of said handle, forming a flexible extension to said handle enclosed within mop material.

20 2. A wringer mop comprising in combination a mop handle, a helical coil of wire attached to one end of said handle providing a flexible extension on said handle beyond the end thereof, said coil having a shoulder formed in its outer face by the turns of said coil, a sleeve rotatably and slidably mounted on said handle and mop material attached to said sleeve covering said coil, a ring tying said mop material against the shoulder of said coil beyond the end of said handle and a second ring uniting said material beyond the end of said coil forming a soft and flexible extension on said handle.

25 3. A wringer mop comprising in combination a mop handle, threads on one end of said handle, a threaded socket in engagement with the threads on said handle, a coiled spring on said socket extending beyond the end of said handle, a sleeve slidably and rotatably mounted on said handle, mop material tied to said sleeve and to lie against the outside of said coil spring to cover the same, the turns of said 30 spring providing a yielding support for said mop material and forming means to prevent rotary motion of said mop material on said spring.

40 4. A wringer mop comprising in combination a mop handle having a thread on one of its ends, a helical coil of wire engaging the threads on said handle and extending beyond the end thereof the thread engaging turns of said coil being of larger diameter than those 45 beyond said handle providing a shoulder and a flexible extension on said handle, a sleeve slidably and rotatably mounted on said handle, mop material attached to said sleeve and to the cylindrical outside of said flexible extension covering the same and a tie wire ring

pressing said material against said shoulder inhibiting longitudinal movement of said material on said coil.

5. A wringer mop comprising in combination a mop handle having a thread on one of its ends, a helical coil of wire engaging the threads on said handle and extending beyond the end thereof forming a flexible extension on said handle, a sleeve slidably and rotatably mounted on said handle, mop material attached to said sleeve and to the flexible extension of said coil and a tie wire pressing said material into the space between two turns of said coil for clamping the same against rotary movement.

Signed at Brooklyn, in the county of Kings and State of New York, this 24th day of July, A. D. 1929.

HARRY HERTZBERG.
